UNITED STATES PATENT OFFICE.

CHARLES H. SCHUH, OF BROOKLYN, NEW YORK.

CATHODE FOR THE ELECTROLYTIC REFINING OF METALS.

Application filed September 22, 1922. Serial No. 589,945.

To all whom it may concern:

Be it known that I, CHARLES H. SCHUH, a citizen of the United States, and a resident of the borough of Brooklyn, city of New

5 York, State of New York, have invented a new and useful Improvement in Cathodes for the Electrolytic Refining of Metals, of which the following is a specification, containing a full detailed explanation of the 10 principle of the invention, and the best manner in which I have contemplated its application, all worded so as to enable those skilled in the art to which it appertains to make and use the same.

15 My invention relates to an improvement in the electrolytic refining of metals.

It is particularly useful in the refining of copper from its ores and other sources of the crude metal by the aid of the electric current.

20 It is especially concerned with the formation of a uniform coating of copper, on the so-called cathode "blanks" used in making what are commonly known as cathode starting sheets, and it affords simultaneously an 25 easy, effective and economical method of stripping or removing these sheets from the cathode "blanks," on which they are formed.

In the process of refining metals from 30 their ores, mattes and other sources of supply, it is customary to manufacture first thin starting sheets by the electrolysis of suitable salts of the metal, the metal being dissolved away from the impure anode and being 35 deposited in the form of a coating on the metallic cathode. The removal of this coating, after it has attained the proper thickness, usually one-eighth of an inch, is fraught with considerable difficulty, due to 40 the fact that the copper film or coating, deposited electrolytically, possesses the tendency to adhere firmly to the metallic cathode.

Various means have been devised for the 45 counteraction of this difficulty, such as, the application of a coating of grease, oil, or fat, either mixed or unmixed with graphite, either natural or artificial; and of other similar materials, conducting the electric current, or the simple application of a top- 50 coat of graphite or similar material on the oil under-coat. This method of alleviating the difficulty of removing cathode starting sheets from the "blanks" on which they are formed, is not very effective, for the coating 55 must be applied after each and every time that the starting sheets are stripped;

it entails considerable labor, loss of time in the process, and it is likewise uneconomical, due to the continuous replacement of the oil and graphite films.

I am also familiar with the method of grooving the edges of the cathode "blanks" —a method which is perhaps most widely used at present—so that the starting sheets can be easily separated from the former 65 along the line of the groove. However, when this process is used, a strip of copper is obtained from the three edges of the cathode "blank," which must be sent back to the refining or melting furnace for remelting, 70 entailing a considerable waste of the metal. Furthermore, it often happens that the starting sheets are spoiled when being stripped off the cathodes in this manner, as they are liable to be torn and otherwise injured. 75 This method has been found to be uneconomical, resulting in the loss of time, and involving considerable labor in the removal of the edge strips and their further treatment in the refining process.

80 Similarly, I am entirely cognizant of the art disclosed in United States Patent No. 1,163,337, in which it is shown that a wedge-shaped groove is cut out in the three peripheral edges of the cathode "blanks." 85

This cut is filled with plastic materials which act as non-conductors, or it may be merely left open or void. Such a method is productive of many disadvantages, among 90 which may be mentioned the difficulty of making so small a groove in the peripheral edges of the cathode "blanks" and of filling the same with plastic materials, the irregular deposition of copper around the peripheral edge, due to the fact that a sharp 95 edge and corner are exposed, the subsequent difficulty in removing the starting sheet intact without tearing the same; and the irregular deposition of copper, resulting in a plate of uneven thickness, which constitutes a serious defect in the starting sheets 100 and results in great operating difficulties in the subsequent manufacture of electrolytic copper.

Furthermore, when no insulating filler is used in the groove, cut in the peripheral edges of the cathode "blanks," it has been found that the deposit of copper overlaps the sharp edges and even fills the inside edges of the wedge-shaped or V-shaped groove, bridging the gap.

105 Other methods of facilitating the removal of the cathode starting sheets, such as per-

forating the edges and filling the perforations with non-conductive, plastic compositions, cutting grooves on both sides of the plates and filling the same in similar manner, are known, but they have proven to be either ineffective, uneconomical or too costly to warrant their extensive application.

I am also aware that in the art of electroplating the use of aluminum has been prevalent wherever it has been considered desirable to be able to remove easily the film of plated metal, without the need of using oil or grease coatings over the surface of the cathode. The surface of the aluminum cathode covers over rapidly with a thin invisible film of oxide, which prevents the plated metal from adhering firmly to the cathode. As far as is known, this property of aluminum has not been applied to the electrolytic refining of metals on an industrial scale, and particularly to the electrolytic refining of copper. My invention uses optionally and preferably aluminum metal for the cathode, and consists of a special form of such cathode which renders it possible to obtain these and other advantageous effects, which have not been possible up to the present time in this art.

The object of my invention is to provide an easy, economical, effective and simple means of removing cathode starting sheets from the cathode "blanks" on which they are formed.

A further object of my invention is to secure a uniform coating of the metal, of even thickness throughout while simultaneously effecting the stripping of the sheets of metal from the cathode "blanks."

A further object of my invention is to avoid the loss in time, the additional cost of labor and materials, and the deficiency in the quality of the starting sheets as they are made by former process. In my process of preparing and using cathode "blanks" it is not necessary to use grease or oil compositions, although I do not limit myself merely to the use of metallic cathodes which allow this advantage to be gained.

A further object of my invention is to secure a cathode "blank" from which the starting sheet may be easily stripped and which does not have to be removed from the supporting frame-work, which holds it, either before, during or after the stripping process. My invention accordingly affords a permanent cathode "blank."

A further object of my invention is to make starting sheets, which are provided with hanging strips, so that these starting sheets may be easily attached to the cross-bars, running across the electrolytic cells.

A further object of my invention is to avoid waste of metal, which occurs when using the common forms of cathode "blanks"

both in the removal of the cathode starting sheets therefrom, and in the fastening of the latter to the cross-bars on the electrolytic cells.

My invention may be applied with good results to the electrolytic refining of all metals and in particular to the electrolytic refining of copper from its ores and other sources of supply.

The drawing illustrates by way of example, one way of carrying out this invention, as follows:

Figure 1 represents a cathode blank in elevation.

Figure 2 represents a plan view of such blank.

Figure 3 represents an elevation of the frame in which the cathode blank fits.

Figure 4 represents a plan view of said frame.

Figure 5 represents an assembled cathode form as used in the cell.

Figure 6 represents a plan view of the top piece.

Figure 7 represents a section on the line 7—7 of Figure 5.

The details of my invention are shown in Figures 1, 2, 3, 4, 5, 6 and 7. While these diagrams represent a preferred mode of carrying out the invention, I desire it to be distinctly understood that I do not limit myself just to such modes of application. There are many other forms of design that can be adopted, which will give substantially the same results, but I have found that the design shown in the aforementioned figures is best adapted for my purpose.

Figure 1 represents the cathode "blank" in the form in which it is made to suit my purpose. 8 is the main body of the cathode. 9 are the cut-out strips, which enable the cathode to be conveniently suspended from the cross-bars on the electrolytic cells. 10 represents a beveled edge, made at an angle of 45 degrees, and extending around the three sides of the cathode "blank" and likewise the cut-out top of the "blanks" with the exception of the three top-most edges, as may be clearly seen in the diagram.

11—11 are the perforations in the cut-out strips for fastening the cathode "blanks" to the cross-bar of the electrolytic cell. The thickness of the sheet is optional, and it can be made as thin as may be desired. I would prefer a thickness of 3/40ths of an inch. The width of the bevel is equal to the thickness of the metal. While I have indicated three cut-out strips at the top of the cathode, as being sufficient to support the weight of the metal, nevertheless, any number of strips or lugs may be used as desirable.

I prefer to make my cathode "blank" from aluminum metal or aluminum alloy or brass, for then I do not have to use any grease or

oil composition to facilitate the removal of the starting sheets. However, the "blanks" may also be made from copper and other metals, whereupon it may be necessary to use the usual grease and graphite compositions.

I wish to call special attention to a particular feature of my invention, namely the beveled edge. This form of edge allows me to secure a firm connection between the cathode "blanks" and the supporting frames, as I will disclose in full detail later in these specifications. It also allows me to obtain simultaneously a film of metal of even thickness throughout, which cannot be accomplished by any of the forms of cathode "blanks," specially shaped for an easy and effective removal of the cathode starting sheets, that are known up to the present time. Those familiar with the art of electrolytic refining of metals may know that a decrease in the thickness of the cathode results in the formation of increased thicknesses of metal at those spots where the cathode is thinner than elsewhere. While I prefer to cut a beveled edge in my cathode "blank" for the purpose of securing a good joint between it and the supporting frame work, nevertheless, I protect this decreased thickness of metal in the cathode "blank" in a manner that I will disclose in full detail later in these patent specifications. Furthermore, while the cathode possesses sharp edges, the well-known disadvantage of such construction, namely, the formation of thick knobular deposits of copper around these sharp points and edges, is avoided through the protection afforded by the supporting frame-work. At the same time, all the structural advantages of this angular construction are made available.

Figure 2 is the top view of the aluminum or other metal cathode "blank." The beveled edge is seen at 10. 9 are the cut-out strips. Figure 3 is a side view of the supporting frame-work, which is used to hold the cathode starting sheets. This frame-work is made of any material, resistant to acid solutions, a non-conductor of electricity possessing rigidity and capable of being machined to exact form and size and of retaining its dimensions, even when made in a very thin sheet. I use hard rubber preferably for this purpose, for it not only possesses the aforementioned properties, but it is also cheap, easy to work and shape to the desired form, very resistant to acids and acid solutions and non-warping. There may also be used for the supporting frame-work, such materials as phenol-formaldehyde condensation products, vulcanized fiber board, various treated wood compositions, which may be covered with acid-resistant paint or varnish, and other similar substances and compositions, which do not conduct the electric

current. As has been stated, I prefer to use hard rubber for this purpose, but I do not limit myself solely to the use of such material, there being many other natural and manufactured products which can serve for the same purpose.

The frame is made in the form of a very thin web, substantially about one tenth of an inch, but any desirable thickness may be used in accordance with the conditions. The web is designated by 14 in Figure 3, and is provided with a thicker edge 13, about one quarter of an inch thick, around three of its edges, as is clearly visible from the figure. This edge is provided with a double bevel, so that one cathode "blank" may be inserted on either side of the web. The manner of making this supporting frame-work and the beveled edge is seen further from Figure 4, which is a top view of the construction. The edge 13 is shown provided with the 45 degree bevel 15. This bevel is made accurately to dimensions, so that the beveled cathode "blanks" fit tightly within the frame. This is an important feature of the invention, as a tight-fitting beveled edge means that no deposit of copper can be formed under the sharp edge of the beveled aluminum cathode. It also affords a tight joint between the rubber frame-work and the aluminum cathodes, so that the former is held fast to the latter and supported thereby. This eliminates the necessity of furnishing separate supports for the rubber frame-work, as the aluminum cathodes are themselves supported by means of the top cut-out strips, which are riveted to the cross-bar of the electrolytic cells. The rubber frame-work then hangs from the aluminum cathodes, and while it supports them and protects them, the aluminum cathodes nevertheless also act as supports for rubber frame-work. In order to make this joint between the rubber frame-work and the aluminum cathodes more secure, a rubber cement of the type that may be bought on the market for gluing rubber to metal, may also be used. Furthermore, the tight-fitting beveled edge of the rubber frame-work protects the decreased thickness of metal in the aluminum cathode. This is likewise an important feature of the invention, for if the decreased thickness of metal is left exposed, and copper or other metal is deposited thereon, the deposit becomes knobular, irregular, thicker than the rest of the sheet of metal and also full of air and gas-holes. This is avoided by my invention, as every care is taken to protect decreased thicknesses of metal in the cathode, consequently, all sharp edges and corners, through the medium of the encompassing hard rubber framework.

Figure 5 is a side view of the entire assembled cathode "blank," as I prefer to have

it constructed. The cut-out strips of the aluminum cathode are seen riveted to a cross-bar, one cross-bar serving to fasten two cathodes. In the place of one cross-bar, 5 two may be used, one for each cathode, thus making the suspension of each metallic side of the cathode "blank" individual. In the figure 16 refers to a top-piece, made of the same material as the rest of the supporting 10 frame-work. This is placed right on top of the main piece of the rubber frame-work. It fits flush at the edge 17 and is provided with a beveled part 18, which fits accurately over the bevel 10 of the aluminum cathode. 15 The rubber top-piece is made with three cut-out sections, as may be clearly seen from the top view in Figure 6, so that the metal of the cut-out strips, 9, of the aluminum cathode is left bare, while the intervening 20 spaces are filled with the material of the top-piece. Hence, the metal deposits electrolytically on these cut-out strips 9, giving a starting sheet with corresponding strips or lugs for easy fastening to the cross-bars 25 of the electrolytic cells, in the further stages of the refining process. It is pointed out again that this rubber top-piece affords protection for all decreased thicknesses in the metal of the cathode, so as to avoid any irregular 30 deposits of the metal being formed thereon.

Figure 7 is section through the composite cathode "blank" on the line 7-7. The aluminum cathodes are seen at 8, the web 35 of the rubber frame-work at 14, the rubber top-piece at 16, the tight fitting beveled edges at 18, the cut-out strips of the aluminum cathodes at 9 and the cross-bar of the electrolytic cell at 19.

40 As seen from the above description, my invention affords an important improvement in the art of making cathode "blanks" and stripping cathode starting sheets in the electrolytic refining of metals. I have described a preferred method of making these cathode "blanks," but I do not limit myself to this sole mode of carrying out the invention. It is possible to construct the cathode, so that one sheet of metal only is used and 45 the metal, being refined, may be deposited on both sides of the cathode. In this case the rubber frame-work consists merely of an edge, running around the three sides of the metallic cathode and of the two or more cut-out strips at the top. The ends of these strips may be fastened to the cross-bar of the electrolytic cells, but this is not necessary as the joint between the metal cathode and the rubber end strips may be made tight 55 enough and strong enough by the use of special rubber cements to avoid such additional support. In this case the peripheral edge of the metallic cathode is cut out in the shape of a V, with the apex of the V pointing outwards or downwards. The rub-

ber edge strip has a corresponding V cut in its peripheral edge of exactly the same dimensions, so as to encompass accurately the V-edge of the metallic cathode. In this way the decreased thickness of metal is protected. 70 The thickness of the rubber end strips is exactly the same as that of the metallic cathode. Hence, the deposit of metal may and can be easily removed from the cathode, which is made of aluminum preferably, but 75 which may also be made from other metals. In the latter case it may be necessary to use the usual type of grease and oil compositions to smear over the surface of the metal so as to prevent too tight adherence of the 80 deposited metal thereon.

In the course of my experimentation with the types of cathodes described above, I have also remarked that it is well to make them equally as large or slightly larger but 85 no smaller than the anode. If this is not done, that is, if the cathode is made smaller than the anode, then there is danger of the formation of irregular deposits of the refined metal on the cathode. 90

95 My invention may be applied to the electrolytic refining of all metals, but it has special advantages in the electrolytic refining of copper. While it is primarily intended for such purpose, I expressly state that I do not limit myself to this one field of its application. I have found that new, novel and important effects in the electrolytic refining of metals can be gained by the use of my invention, which I have disclosed in full detail in a preferred mode of application, but in applying for this patent I wish to call attention to the fact that the principles involved therein, the use of aluminum metal or other suitable metals, the formation of an 100 edge to assist in the stripping of the deposited metal, the protection of this edge to avoid irregular deposits on the cathode, the size of the cathode with reference to the size 105 of the anode, are the important features of the invention and not the particular mode in which it is carried out.

110 The term "film-forming metals" is used in the claims to cover such metals as aluminum, aluminum alloys, brass or their equivalents, 115 which are considered to owe their property of formation of easily strippable electrolytic deposits thereon, to the formation of film-forming oxides; and though I preferably claim "film-forming metals," I mean to include as equivalents the cathodes having thin non-conducting or non-adherent coatings, such as formed by coating with grease, oil or graphite or combinations thereof, to aid in the formation of an easy strippable deposit. 120

125 The terms "chamfered" and "tapering away" are used in the claims to refer to an edge which may be beveled, concave, convex, etc., in order to be fitted for use in the disclosed structure. 130

The term "cathode form" is used to include a cathode or cathode blank or equivalent structure.

Having thus described in full detail the principles and construction of my invention, I seek to claim as follows:

1. A cathode comprising a plate having a chamfered edge, said plate adapted to fit a non-conducting frame therefor, said plate comprising a "film-forming metal."
2. A cathode comprising a plate having an edge tapering away from its front face towards its rear face, said plate adapted to fit a non-conducting frame therefor, said plate comprising a "film-forming metal."
3. In an electrolytic cell, a cathode having an area as large at least as the area of the anode.
4. In an electrolytic cell for the refining of copper, a cathode having an effective area as large at least as the area of the anode.
5. A cathode comprising a plate having a chamfered edge, said plate adapted to fit a non-conducting frame therefor.
6. A cathode comprising a plate having an edge tapering away from its front face towards its rear face, said plate adapted to fit a non-conducting frame therefor.
7. In an electrolytic cell, a cathode comprising an edge tapering away from its front face toward its rear face, and means on said plate to prevent access of the solution to the tapered edge.
8. A cathode as set forth in claim 7 in which the means on said plate for preventing access of the solution to the edge is so arranged as not to diminish the exposed effective surface of the plate.
9. A cathode form comprising in combination, a plate having a chamfered edge and a non-conducting framework carried by said plate to prevent exposure of the chamfered edge.
10. A cathode form comprising in combination a plate the upper portion of which is cut away to form suspending members the peripheral edges of the plate and the suspending members being beveled.
11. A cathode form comprising in combination a plate having a portion of its upper body cut away to form suspending members, the edges of the plate and the suspending members being chamfered, a framework adjacent said plate to prevent exposure of the edges of the plate, and a top-piece adjacent said suspending members to prevent exposure of the edges of those members.
12. A cathode form comprising a plate having its edges tapered to provide an outwardly directed V-shaped edge adapted to fit a non-conducting frame therefor.
13. A cathode form comprising in combination, a plate having its edges beveled to provide an outwardly directed V-shaped edge, and means adjacent such edge to prevent its exposure to the action of an electrolytic solution when submerged or immersed therein.
14. A cathode form as set forth in claim 13, in which the means for preventing exposure of the edge comprises a framework having an inwardly directed V-shaped surface adapted to fit snugly against the edge of the plate.
15. In a cell for the electrolytic refining of copper, a cathode form comprising an aluminum plate having its edge tapering from its front face toward its rear face, the effective area of the plate being as large, at least, as the area of the anode.
16. A cathode form comprising in combination, a greasy metal plate having a beveled edge, said plate being cut away in its upper body portion to provide suspending members, the edges of the suspending members being beveled, a hard rubber framework adjacent the plate and beveled to fit snugly against the edge of the plate, and a hard-rubber top-piece having a beveled surface to enable it to fit snugly against the edges of the suspending members.
17. In an electrolytic cell for the refining of copper, a cathode form comprising an aluminum plate having a portion of its body cut away to provide suspension members, the edges of the plate and suspension members tapering from the front face towards the rear face of the plate, a hard rubber framework adjacent said plate beveled to fit snugly against the edge of the plate without diminishing the area of the front face of the plate, and a hard rubber top-piece adjacent the suspension members beveled to fit snugly against the edges of the suspension members without diminishing the exposed surface of the front face of those members, said cathode form having an effective surface as large, at least, as the effective surface of the plate.
18. A cathode form comprising a metallic plate and a framework adjacent said plate to prevent access of the solution of an electrolytic cell to the edges of the plate without diminishing the surface of the front face of the plate, when said plate is used in an electrolytic cell.
19. A cathode form comprising in combination a plate having a chamfered edge and a framework carried by said plate, said framework being flush with the effective depositing surface of said plate.
